Glenn C. Steele.

UNITED STATES PATENT OFFICE.

GEORGE H. NEARING, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

SNAP-HOOK.

SPECIFICATION forming part of Letters Patent No. 768,817, dated August 30, 1904.

Application filed January 27, 1904. Serial No. 190,777. (No model.)

To all whom it may concern:

Be it known that I, GEORGE H. NEARING, a citizen of the United States, residing at New Britain, in the county of Hartford, State of Connecticut, have invented certain new and useful Improvements in Snap-Hooks, of which the following is a full, clear, and exact description.

My invention relates to snap-hooks.

The object of the invention is to construct a snap-hook in a simple and inexpensive manner, which may nevertheless be very strong and readily operable.

The invention consists of three parts—a body portion, a tongue portion, and a spring for holding the tongue and body in their proper operable relations—all constructed and assembled substantially as shown.

In the preferred form of my invention a plate having a slot is provided by which the snap-hook may be readily attached to a strap or like structure; but the hook obviously may be attached in other ways.

The invention has particular advantage with that class of fasteners used in connection with harnesses, blankets, hitch-lines, saddlery, &c. It may also be used for book-straps and with proper modifications for suspender-cast-offs and other structures requiring a snap-hook fastener.

The details of construction will be seen on an inspection of the accompanying single sheet of drawings, in which—

Figure 1 is a perspective view illustrating the preferred form of my invention. Fig. 2 is a side elevation of the parts of the snap-hook at one stage of the process of assembling. Fig. 3 is a detail plan view of the tongue member. Fig. 4 is a side elevation of a very slightly modified form of my invention riveted to some rigid support and showing the operation of releasing the hook.

1 indicates the body portion of the hook. 2 is a recess therein. 3 is a spring situated in said recess.

4 is a tongue having a pivot 5. The pivot of this tongue has bearings at the rear of the

body portion and is held in place by the shoulder 6. This shoulder 6 is bent down in place in the process of assembling the parts, as will be clearly understood from an inspection of Fig. 2. The spring is inserted in a recess of the body portion with its ends toward the pivot-recess, the tongue slipped under the bill of the hook with the pivot in front of the shoulder. The pivot is then pressed downward and the shoulder 6 bent over to hold the parts in place, where they are securely locked against accidental displacement.

7 is a plate which extends from the pivotal portion of the tongue member and by means of which the snap-hook is attached to whatever is desired. The tongue is arched at 8, and thus provides a convenient position for operating the tongue by means of the finger 65 and also provides a clearance on the under side for the spring. This will be seen particularly on inspection of Fig. 4.

My particular object in combining the tongue and loop members is to make it convenient to open the snap-hook without pressing down upon the tongue with the finger. This method of opening it is shown also clearly in Fig. 4, where the tongue-plate 7' is held stationary by the part to which it is attached, 75 while the eye 9 as it engages the bill of the hook pulls the bill outward, so that the eye may then be slipped off upward.

The body portion of the tongue and loop are preferably made of malleable iron, while the spring is preferably made of tempered steel.

It will be obvious to one skilled in the art that many changes in the details of construction might be made without departing from the spirit or scope of my invention. For instance, in the form of spring, or, as above suggested, a rivet-plate 7' might be used in place of the loop, as in Fig. 4. The parts are so assembled that they will not be separated even by the accidental breaking of the spring.

What I claim is—

A snap-hook comprising in combination, a body portion having a bill at one end, a shoul-

der at the other, and a pair of flanges near said shoulder forming a recess between them and forming pivot-bearings adjacent said shoulder, a tongue member with pivots resting in the pivot-bearings, said shoulder being bent forward over said pivots and said flanges, fastening means carried by said tongue mem-

ber, and a spring located in said recess for the purpose specified.

GEORGE H. NEARING.
